(57) **CLAIM**

The ornamental design for a luminaire, as shown and described.

DESCRIPTION

FIG. 1 is a perspective view of a luminaire of the present invention;

FIG. 2 is a left side elevational view of the luminaire of FIG. 1, the right, opposite, side of which is a mirror image thereof;

FIG. 3 is a front elevational view of the luminaire of FIG. 1;

FIG. 4 is a rear elevational view of the luminaire of FIG. 1;

FIG. 5 is a top plan view of the luminaire of FIG. 1;

FIG. 6 is a bottom plan view of the luminaire of FIG. 1;

FIG. 7 is a perspective view of a second embodiment of the luminaire of the present invention;

FIG. 8 is a left side elevational view of the luminaire of FIG.

7, the right, opposite, side of which is a mirror image thereof;

FIG. 9 is a front elevational view of the luminaire of FIG. 7,

the rear, opposite, side of which is a mirror image thereof;

FIG. 10 is a top plan view of the luminaire of FIG. 7; and,

FIG. 11 is a bottom plan view of the luminaire of FIG. 7.

The broken lines shown are for illustrative purposes only

and form no part of the claimed design.
